Primary Examiner—Susan Moon Lee(74) *Attorney, Agent, or Firm*—Frishauf, Holtz, Goodman & Chick, P.C.(57) **CLAIM**

The ornamental design for a bar code reader, as shown and described.

DESCRIPTION

FIG. 1 is a front, top and right side perspective view of a bar code reader showing my new design in accordance with an embodiment;

FIG. 2 is a front elevational view thereof;

FIG. 3 is a rear elevational view thereof;

FIG. 4 is a top plan view thereof;

FIG. 5 is a bottom plan view thereof;

FIG. 6 is a right side elevational view thereof; and,

FIG. 7 is a left side elevational view thereof.
